UNITED STATES PATENT OFFICE.

JOHN ROGERS, OF NEW CANAAN, CONNECTICUT.

DESIGN FOR A GROUP OF STATUARY.

SPECIFICATION forming part of Design No. 12,039, dated November 23, 1880.

Application filed September 3, 1880. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying photographic illustration, forming part thereof.

10 The name of the group is "The Referee," and this is marked on the base. It consists of three figures, and represents two ladies standing back to back, and an old gentleman measuring to see which is the taller. The one 15 in the front ground stands erect, holding a fan in her left hand and the folds of her overskirt in her right. This skirt is cut open from her waist down, showing a quilted underskirt with puffs round the lower part. She wears a 20 stiff lace collar, and has her hair drawn straight back from her face. The lady in the background is standing on tiptoe, and is looking partly round and smiling. She wears a light shawl over her shoulders, and her skirts are gathered up from her feet. The old gentleman 25 has his left hand over the tops of their heads, and is looking to see the difference in their heights. He is resting on his umbrella in his right hand, in which he also holds his cocked hat. He wears his hair drawn back in the 30 old style, and a ruffle shirt.

I claim and desire to secure by Letters Patent of the United States—

The design for a group of statuary called "The Referee," and consisting of an old gentleman measuring the height of two ladies, one of whom is standing on tiptoe, substantially as described in the foregoing specification, and shown in the accompanying photographic illustration.

JOHN ROGERS.
